SCREW AND TOGGLE ADJUSTED WRENCH
AND CLAMP

Henry Alpers, Columbus, Nebr.

Application October 25, 1945, Serial No. 624,420

2 Claims. (Cl. 81—84)

1

This invention relates to a combination wrench and clamp, which can be employed for use as pliers, ratchet wrench or pipe wrench.

An object of the invention is to provide a device having a stationary jaw and a movable jaw and means for moving the movable jaw relative to the stationary jaw.

Another object of the invention is to provide a device which is efficient in operation, simple in construction and inexpensive to manufacture.

With these and other objects and advantages in view, the invention consists of the novel details of construction, arrangement and combination of parts more fully hereinafter described, claimed and illustrated in the accompanying drawings in which:

Figure 1 is a view in side elevation of an embodiment of the invention;

Figure 2 is a longitudinal section thereof with the movable jaw in locked position;

Figure 3 is the same with the movable jaw in position to be moved longitudinally of the body;

Figure 4 is a sectional view on the line 4—4 of Figure 1;

Figure 5 is a side view of the clutch member;

Figure 6 is a bottom view thereof;

Figure 7 is a side view of one type of jaw face;

Figure 8 is a sectional view thereof;

Figure 9 is a side view of another form of jaw face, and

Figure 10 is a sectional view thereof.

Referring more in detail to the drawings, the numeral 20 designates the shank of the wrench which is U-shaped in cross section and is provided with opposed apertured stationary jaw receiving portions 22. The jaw receiving portions 22 are formed at right angles to the shank at the forward end thereof and are adapted to receive the stationary jaw 24 therein. The jaw 24 being retained in position in the portions 22 by rivets 26.

Mounted in the shank 20 is the rotatable adjusting and locking screw 28. One end of the screw 28 is enlarged at 30 which is seated in a bearing socket 32 provided in the jaw 24. Upon the other end of the screw 28 is mounted a knob 31 and a bearing socket 33 mounted in the shank 20 and secured thereon by rivets 35 seats this end of the screw 28. The knob 31 extends beyond the outer end of the socket 33 for the easy manipulation thereof.

A U-shaped member 34 which is slidably mounted on the shank 20, comprises the bottom portion 36 and side portions 38. An upstanding apertured ear 40 is formed on each side portion at one end thereof and inwardly turned and over-

2

ing apertured ears 42 on the opposite ends of the side portions. The apertured grip or locking member 44 is secured to the overlapping ears 42 by means of the rivet 46.

The movable jaw comprises the side portions 48 and the intermediate jaw portion 50 which are secured together by rivets 51. The movable jaw is pivoted at its inner end to the ears 40 of the member 34 by means of a pivot bolt 54. The pivot bolt 54 extends through the ears 40 and the jaw portion 50 and a nut 56 on the end thereof retains the bolt in position.

The stationary and movable jaw portions 24 and 50 are provided with removable teeth members 52 which are retained in position on each jaw by a pin 53. The pin 53 is fixed in the jaw portions 24 and 50 and extends through the apertured end 54 of each plate 56. A serrated portion 58 is secured by means of rivets 60 to each plate 56, as shown in Figures 9 and 10. A nut 62 on each pin 53 retains each of the plates in position on each jaw portion. One end of the plate 56 on the jaw portion 50 is curved at 64 to fit the jaw portion 50 while the end on the jaw portion 24 remains straight as shown.

The hand lever 66 is pivotally connected to the movable jaw by one of the rivets 51 which acts as a pivot pin therefor. Between the portions 48 of the movable jaw, the portion 50 has a curved recess 68 in the forward end thereof to permit movement of the lever 66.

The hand lever 66 is pivotally supported adjacent its forward pivoted end between a pair of curved arms 72 by a pivot pin 70. The arms 72 extend laterally from the shank 20 and are pivotally connected to the clutch member 74, which is slidably mounted in the shank 20, by means of pivot pin 76.

The clutch member 74 comprises a block member 78 which is apertured at each end transversely thereof to receive the pin 76 and one of the rivets 51 whereby said member is pivotally connected to the movable jaw. The end of the member 78 is recessed at 80 at the end pivoted to the movable jaw to compensate for the curved end 64 of the teeth securing plate 56.

Welded to the member 78 is the plate 81 having screw threads 82 which co-act with the screw 28 for adjustment thereof.

The forward end of the plate 80 is pointed and inclined at 84 and is positioned rearwardly of the forward end of the member 78. The rear end 86 of the plate 81 extends beyond the rear end of the member 78 and is provided with the upstanding pin 88 which is received in the apertured ears

42 and grip 44. The pin 88 extending upwardly through the ears 42 and grip 44 is adapted to be contacted by the hand lever 66. Therefore, when the lever 66 is in the position shown in Figure 2, the pin 88 is forced downward thereby forcing the plate 80 into full contact with the screw 28.

A spring 89 fastened to a pin 90 carried by the arms 72 and an apertured pin 92 fixed to the hand lever 66 aids in forcing the lever into the position shown in Figure 3 when it is released from operative position.

In Figures 7 and 8, the plate 56 has a face 94 secured thereto by rivets 96. The face 94 is adapted for use with highly polished or easily damaged articles, since it comprises a covering 96 and an intermediate pad 98. However the remainder of the plate formation is the same as previously described.

In the use of the wrench, the lever is moved outwardly until the clutch member is disengaged from the screw, then the movable jaw can be moved to grip the article desired for retention between the jaws by depressing the lever. Thus the movable jaw is locked in position for use. Slight pressure on the lever will permit the clutch member to be adjusted by the knob on the end of the screw, but full pressure will securely lock the movable jaw in position.

It is believed that the operation and construction of the wrench will be apparent to those skilled in the art and that a device has been provided that will accomplish the objects of the invention.

It is to be understood that changes and modifications in the various parts and combinations thereof may be resorted to without falling beyond the spirit of the invention or the scope of the appended claims.

Having thus described the invention, what is

claimed as new and desired to be secured by Letters Patent is:

1. A device of the character described, comprising a shank which is U-shaped in cross-section having opposed jaw receiving portions, a fixed jaw secured intermediate of and to said jaw portions, a member slidably mounted on said shank, a movable jaw pivoted to said member, a hand lever pivoted at one end to said movable jaw, supporting arms intermediate the sides of said slideable member, means carried by said arms for pivotally supporting said hand lever intermediate of said arms, a screw mounted in said shank and clutch means pivotally mounted on said supporting arms adapted to co-act with said screw to lock said movable jaw in fixed position with relation to said fixed jaw said clutch means comprising a block member pivoted at one end to said movable jaw and at the other end to said supporting arms and a plate member secured to the undersurface of said block member having screw threads therein to coact with said screw.

2. The invention as in claim 1, said movable jaw comprising side portions having the jaw portion positioned intermediate thereof and means for holding said portions in assembled relation to each other.

HENRY ALPERS.
